United States Patent Office.

JOHN A. HEMBERGER, OF READING, OHIO.

Letters Patent No. 96,233, dated October 26, 1869.

IMPROVED GUTTER FOR DOOR-SILLS.

The Schedule referred to in these Letters Patent and making part of the same.

I, JOHN A. HEMBERGER, of Reading, in the county of Hamilton, and State of Ohio, have invented a certain new and useful Weather-Guard, or Gutter, for Door-Sills, of which the following is a specification.

This is an improvement in the class of gutters provided in the sills of outside doors, for catching and conducting off whatever rain may beat or be drifted in from the outside.

The first part of my invention relates to a flap, or cover, hinged to the inner margin of the gutter, and to which the edge of the carpet may be fastened, which flap being slightly elevated, conducts all the rain into the gutter.

The second part of my invention relates to a provision for automatically lifting the flap, in and by the act of closing the door.

The third part of my invention relates to a means of suspending the action of the lifting-device.

Figure 1 is a perspective view of a double door, provided with my improvement, and with one of the flaps thrown wide open, so as to expose the gutter.

Figure 2 is a vertical section through the lower portion of the door, the flap being shown in its elevated or effective position.

A and B represent the two members of a double door, of which each member has in its sill a gutter, C, whose bottom declines toward the door-jamb, and discharges by suitable spout, D, which passes to the outside of the building.

In order to hide the gutter C from view, and that it may offer no obstruction to the passage, and also to prevent the rain beating into the room, I provide a flap or deflector, E, which is hinged to the inner edge of the gutter, or to the sill on that side. This flap being set open by a wedge or other device, when

the door is shut, arrests the rain as it enters the room beneath the door, and conducts it into the gutter C.

The opening of the flap by the act of closing the door may be rendered automatic by the following means:

One end of the sill is excavated to receive a lever, F, whose outer portion f', when the door is open, is slightly elevated by the weight of the flap upon its inner portion f, but on closing the door is depressed by a projection from the door, so as to elevate the edge of the flap.

This projection may consist of a bolt, G, whose handle g occupies a slot, H, in the door, said slot having notches h h' for retaining the bolt, either in its effective or non-effective position.

Slots or apertures e in the flap, near its outer edge, enable the attachment of a carpet or other floor-covering.

My improvement is equally applicable to single or to double doors.

I claim, as my invention—

1. The provision of the gutter C and flap or deflector E to a door-sill, substantially as set forth.
2. The arrangement of the door-sill gutter C, hinged flap or deflector E, lever F, and bolt or other projection G, substantially as set forth.
3. In the described combination with the elements C, E, and F, the bolt G and slot H, or their equivalents, for the objects designated.

In testimony of which invention, I hereunto set my hand.

JOHN A. HEMBERGER.
